UNITED STATES PATENT OFFICE.

ULRICH TOBLER, OF PFORZHEIM, GERMANY, ASSIGNOR TO THE FIRM OF BROCKDORFF-
WITZENMANN M. B. H., OF BERLIN, GERMANY.

ELECTRODE-TERMINAL FOR ELECTRIC HEATERS.

1,101,360.

Specification of Letters Patent. Patented June 23, 1914.

Application filed January 15, 1914. Serial No. 812,276.

To all whom it may concern:

Be it known that I, ULRICH TOBLER, citizen of the Confederation of Switzerland, residing at Pforzheim, Germany, have invented certain new and useful Improvements in Electrode-Terminals for Electric Heaters, of which the following is a specification.

This invention relates to electric fluid heaters, as for example electric steam generators, and relates more particularly to an improved terminal or binding post for securing the current conductor or lead, which conducts the current to the terminal, to the heater casing.

My invention relates to that type of terminal in which the lead, which passes through an aperture in the heater casing, is surrounded by an insulating tube of porcelain or the like which is secured to the heater casing.

The object of the present invention is to provide a terminal which dispenses with the necessity of cemented joints and thus enables high pressures and high temperatures to be generated in the heater without the danger of leakage occurring at the terminal, the parts constituting the terminal being for this purpose provided with fluid-tight packed joints which will, however, allow a certain amount of play so as to permit of the expansion of the different parts on an increase in temperature.

The preferred construction of my improved terminal is illustrated on the accompanying drawing in section.

The current is supplied to the terminal by way of the binding post *a* of a conductor or lead *b* which may consist of a brass wire or rod, the current passing from the terminal through the liquid to be heated to the second terminal. The lead *b* passes through the casing *l* of the heater, and is insulated by a surrounding insulating tube *c* preferably of porcelain, the tube *c* also passing through the casing *l* and being surrounded by a hood or cover *d* secured to the casing *l* so as to close the aperture therein. The upper end of the hood or cover *d* is recessed internally to form a shoulder *d'*, an enlarged part *c'* on the porcelain tube *c* fitting upon this shoulder *d'* so as to support the porcelain tube. A ring nut *h* screwed on to the lower end of the hood or cover *d* guides the tube *c* and gives lateral support thereto. A

fluid-tight joint is formed between the upper end of the hood *d* and the porcelain tube *c* by means of a packing *e* adapted to be compressed by means of a gland *m*. If desired, as shown on the drawings, a second packing *f* may be inserted between the gland *m* and the tube *c* and this packing compressed by means of a gland *n*.

Welded upon the lead *b* is a ring *g* adapted to fit against an internal shoulder *s* formed in the tube *c*, a packing ring *h* being interposed between the ring *g* and shoulder *s*. The ring *h* is pressed firmly against the packing ring *g* which in turn bears against the shoulder *s* by means of a nut *i* on the end of the lead *b* and also by the pressure within the heater, thus preventing leakage.

It will be understood that the terminal described herein is such as may be used for heating liquids to a very high temperature and it is to be understood that the terminals may be placed conveniently upon the vessel containing the liquids to be heated, a portion of the vessel being indicated at *l* in the drawings.

I claim:

1. A terminal for electric fluid heaters in which the lead passes through an aperture in the heater casing, comprising an insulating member surrounding said lead, a fluid-tight joint interposed between said lead and member, a cover over said aperture and through which said member passes and a fluid-tight expansible joint between said cover and member.

2. A terminal for electric fluid heaters in which the lead passes through an aperture in the heater casing, comprising an insulating member surrounding said lead, packing forming a fluid-tight joint between said lead and member, a cover over said aperture and through which said member passes and packing forming a fluid-tight joint between said cover and member.

3. A terminal for electric fluid heaters in which the lead passes through an aperture in the heater casing, comprising a ring on said lead, an insulating tube surrounding said lead and having an internal shoulder, packing between said shoulder and ring, a cover over said aperture and through which said tube passes and a fluid-tight joint between said cover and tube.

4. A terminal for electric fluid heaters in which the lead passes through an aperture

in the heater casing, comprising an insulating member surrounding said lead and having an enlarged part, a fluid-tight joint between said lead and member, a tubular member secured to the heater casing and fitting said aperture, said tubular member having an internal shoulder adapted to receive said enlarged part, packing between the outer ends of said insulating member and tubular member and a gland for compressing said packing.

5. A terminal for electric fluid heaters in which the lead passes through an aperture in the heater casing, comprising a ring on said lead, an insulating tube surrounding

said lead and having an internal shoulder, packing between said shoulder and ring, an enlarged exterior part on said tube, a tubular cover secured to the heater casing and fitting said aperture, said cover having an internal shouldered recess at its outer end adapted to receive the enlarged part of the tube, packing in said recess and glands for compressing said packing.

10 In testimony whereof I have affixed my signature in presence of two witnesses.

ULRICH TOBLER.
